(57) **CLAIM**

The ornamental design for a remote control as shown and described.

DESCRIPTION

1. Remote control

Fig. 1.1 is a top plan view of the remote control;

Fig. 1.2 is a bottom plan view thereof;

Fig. 1.3 is a perspective view thereof;

Fig. 1.4 is a side elevation view thereof;

Fig. 1.5 is a rear elevation view thereof; and

Fig. 1.6 is a front elevation view thereof.

Handheld control unit for unmanned systems.
